UNITED STATES PATENT OFFICE

102,526

DESIGN FOR A LIGHTING FIXTURE

Joseph Stutz, Los Angeles, Calif., assignor to
Solar Lighting Fixture Company, Los Angeles,
Calif., a corporation of California

Application November 23, 1936, Serial No. 66,092

Term of patent 7 years

To all whom it may concern:

Be it known that I, Joseph Stutz, a citizen of the United States, residing at Los Angeles, in the county of Los Angeles and State of California, have invented a new, original, and ornamental Design for a Lighting Fixture, of which the following is a specification, reference being had to the accompanying drawing, forming part thereof, in which

Fig. 1 is a top plan view, the support shown in Fig. 3 being omitted.

Fig. 2 is an elevational view.

Fig. 3 is a vertical section taken on the line 3—3 of Fig. 1 of a lighting fixture showing my new design.

The characteristic features of my design reside in the four annular louvers, each provided with a rolled peripheral edge, the body of each louver being curved inwardly and downward, said louvers being spaced from each other, the three lower louvers being of the same diameters, the fourth louver, which is positioned on top, being of considerably larger diameter than the other three.

I claim:

The ornamental design for a lighting fixture, as shown and described.

JOSEPH STUTZ.
